2,677,980

WALL MOUNTED BOTTLE OPENER

Jerry J. Dika, Detroit, Mich.

Application March 15, 1952, Serial No. 276,860

3 Claims. (Cl. 81—3.3)

1

The present invention relates to an improved bottle opener of the type used for removing conventional type bottle caps, such as those commonly employed on soft drink or beer bottles and sometimes referred to as crown type bottle caps.

It is an object of the present invention to provide an improved bottle opener of the above mentioned type which is simple in design, economical of manufacture and reliable and efficient in operation.

It is a further object of the present invention to provide an improved bottle opener of the above mentioned type which may be collapsed to an inoperative position in which it occupies a minimum of space and presents no rough edges upon which clothing or the like may be caught.

It is also an object of the present invention to provide an improved bottle opener of the above mentioned type including spring means for yieldably holding the opener in the collapsed position and yieldably holding the opener in its open or operative position.

Other and more detailed objects of the invention will be appreciated by those skilled in the art from a consideration of the specification, the appended claims and the accompanying drawing wherein:

Figure 1 is an elevational view of an embodiment of the present invention mounted on an associated wall and in its operative position and showing a portion of a bottle in position for removal of the cap mounted thereon;

Figure 2 is an elevational view similar to Figure 1 showing the bottle opener in its collapsed or inoperative position;

Figure 3 is an enlarged front elevational view of the structure illustrated in Figure 2 looking in the direction indicated by the arrow 3;

Figure 4 is a sectional view of the structure illustrated in Figure 3, taken substantially along the line 4—4 thereof;

Figure 5 is a broken sectional view of the structure illustrated in Figure 3, taken substantially along the line 5—5 thereof; and,

Figure 6 is a sectional view of the structure illustrated in Figure 4, taken substantially along the line 6—6 thereof.

Figure 7 is a broken enlarged sectional view of the upper end portion of the arm as seen in Figure 4.

Referring to the drawing, the bottle opener of the present invention generally comprises a wall bracket 10 which is provided with apertures at the upper and lower ends thereof for receiving screws 12 for mounting the bracket 10 on a wall

2

14 or other suitable supporting structure, and an arm generally indicated at 16 which is pivotally mounted on the bracket 10 for movement between an open or operative position illustrated in Figure 1, and a collapsed or inoperative position illustrated in Figure 2.

In the preferred embodiment illustrated, the bracket 10 is formed of a generally flat and rectangular plate having a transversely extending and forwardly offset portion 18 which defines a recess 20 extending transversely of the plate 10 at the rear side thereof, and a shallow depression 22 extending downwardly from the recess 20, as viewed in the drawing.

15 The forwardly offset portion 18 also has a slot 24 therethrough extending transversely of the plate 10. At the upper side of the slot 24 the plate 10 is formed to provide a surface indicated at 26 (see Figure 4) adapted to engage the arm 16 when the latter is in its operative position. The plate 10 is also provided with a transversely extending slot 28 spaced below and extending parallel to the slot 24. At the lower side of the slot 28 the plate 10 is distorted outwardly to provide a projection or stop 30 for engaging the bottle cap 32, as illustrated in Figure 1, during removal thereof from a bottle 34.

The arm 16 has an inwardly turned outer end portion 36 terminating in an arcuately shaped end 38 adapted to fit the bottle 34 adjacent the lower edge 40 of the cap 32 as illustrated in Figure 1. Adjacent its opposite end the arm 16 extends through the slot 24 in the forwardly offset portion 18 of the plate 10 and has a pair of integrally formed laterally extending fingers generally indicated at 42 and which include portions 44 extending at an angle to the adjacent portion of the arm 16 and which, upon movement of the arm 16 to the operative position illustrated in

30 Figure 1, are moved into the depression 22 and into engagement with the portion of the plate 10 defining the depression 22. Intermediate the laterally extending fingers 42 the inner end of the arm 16 is notched and has a pair of surfaces 46 and 48 inclined relative to each other and adapted to be engaged by a spring. It will be appreciated that in the broader aspects of the present invention any suitable spring means may be employed including a spring finger formed integrally with the plate 10. In the preferred embodiment illustrated a separate flat spring strip

40 50 is mounted at the rear side of the plate 10 in a centrally disposed downward extension of the depression 22 and secured adjacent its lower end 55 to the plate 10 by a rivet 52. The spring 50

engages the arm surface 46 when the arm 16 is in the inoperative position illustrated in Figure 2, to yieldably hold the arm 16 in this position, and engages the arm surface 48 when the arm 16 is in the operative position illustrated in Figure 1 to yieldably hold the arm in this position.

It will be noted that in the preferred embodiment illustrated the plate 10 and the arm 16 are so formed that when the arm 16 is in its operative position the upper side thereof engages the surface 26 at the upper side of the slot 24 and the fingers 42 engage the rear side of the plate 10 at the lower side of the recess 20 and the portions 44 of the fingers 42 are disposed in the depression 22 and engage the rear side of the plate 10 within the depression 22. These engagements all co-operate to prevent pivotal movement of the arm 16 in a clockwise direction beyond the operative position illustrated in Figure 1.

When the arm 16 is in the inoperative position illustrated in Figures 2 through 6, inclusive, the inwardly turned end portion 36 extends into the slot 28 to render the bottle opener more compact and to seal the corners of the arcuately shaped end 38 to prevent the catching of clothing or the like on these corners.

In the preferred embodiment illustrated the plate 10, the arm 16 and the spring 50 are so proportioned that at no time does the spring 50 or the upper end of the arm 16 extend rearwardly beyond the plane of the rear surface 54 of the plate 10. This insures that the supporting structure 14 will not interfere with the movement of the arm between its inoperative and operative positions.

It will be appreciated from the above description of the bottle opener of the present invention that a bottle cap 32 is removed from a bottle 34 by means of the bottle opener of the present invention by moving the arm 16 to its operative position illustrated in Figure 1 and positioning the bottle 34 as there illustrated so that the inwardly turned outer end portion 36 of the arm 16 engages the lower edge 40 of the cap 32 and the cap 32 at its opposite side engages the plate 10 at the point indicated by the reference character 56. Upon movement of the bottle 34 to pivot about the engagement of the cap 32 with the plate 10 at the point 56, the arm 16 will pull the cap 32 from the bottle. The projection or stop 30 may be omitted if desired. It is disposed to prevent the cap 32 from sliding upwardly along the plate 10 during this cap removing movement.

While only one specific embodiment of the invention has been illustrated and described herein in detail, it will be readily appreciated by those skilled in the art that numerous modifications and changes may be made without departing from the spirit of the present invention.

What is claimed is:

1. A bottle opener, said opener comprising a wall bracket adapted to be secured to a wall or other suitable support, an arm pivotally mounted on said wall bracket for movement between an inoperative position in which it extends along said wall bracket substantially parallel thereto and an operative position in which it extends outwardly therefrom at a substantial angle relative thereto, said arm having an inwardly turned outer end portion to engage a bottle cap at its lower edge when said arm is in said operative position, said wall bracket having a portion to abuttingly engage a cap at the side of the cap opposite the engagement of the cap by said inwardly turned outer end portion of said arm.

5 whereby said outer end portion of said arm is effective to pull the cap from the bottle upon pivotal movement of the bottle downwardly about the point of engagement of the wall bracket with the cap, said bracket having a forwardly offset portion defining a recess at the rear of said bracket and a shallow depression below and communicating with said recess, said offset portion having a slot therethrough, said arm extending through said slot and having laterally extending fingers disposed in said recess, said fingers including portions extending at an angle to the adjacent portion of said arm and adapted upon movement of said arm to said operative position, to move into said depression and engage the rear side of said bracket.

2. A bottle opener for removing the conventional type bottle caps used on soft drink or beer bottles, said opener comprising a wall bracket adapted to be secured to a wall or other suitable support and having a forwardly offset portion defining a recess at the rear of said bracket and a shallow depression below and communicating with said recess, said forwardly offset portion of said bracket having a slot therethrough, and said bracket having a second slot spaced from and below said forwardly offset portion and extending generally parallel to said first named slot, an arm extending through said first named slot and having laterally extending fingers, said arm having an inwardly turned outer end portion to engage a bottle cap at its lower edge, and spring means disposed at the rear side of said bracket and mounted in said depression and engaging said arm, said arm being pivotally movable relative to said bracket between an inoperative position in which said arm extends generally parallel to said bracket and in which said inwardly turned outer end portion of said arm is received in said second slot and an operative position in which said arm extends outwardly from said bracket at a substantial angle relative thereto and in which said arm engages said bracket at one side of said first named slot and said fingers engage said bracket at the rear side thereof to co-operate with said just mentioned engagement of said bracket by said arm to prevent pivotal movement of said arm beyond said operative position, said bracket, said arm and said spring means being so constructed and arranged that said spring means yieldably holds said arm in each of said positions and neither said spring means nor said arm extends rearwardly of the rear surface of said bracket at any time.

3. A bottle opener for removing the conventional type bottle caps used on soft drink or beer bottles, said opener comprising a wall bracket adapted to be secured to a wall or other suitable support and having a forwardly offset portion defining a recess at the rear of said bracket, said forwardly offset portion having a slot therethrough communicating with said recess, an arm extending through said slot and into said recess and having laterally extending fingers disposed in said recess, said arm having an inwardly turned outer end portion to engage a bottle cap at its lower edge, and spring means disposed at the rear side of said wall bracket and extending into said recess and engaging said arm, said arm being pivotally movable relative to said bracket between an inoperative position in which said arm extends generally parallel to said bracket externally thereof and an operative position in which said arm extends outwardly from said bracket at a substantial angle relative thereto and in which

said arm engages said bracket at the upper side of said slot and said fingers engage said bracket at the rear side of said bracket to co-operate with said just mentioned engagement of said bracket by said arm at the upper side of said slot to prevent pivotal movement of said arm beyond said operative position in a direction away from said inoperative position, said bracket, said arm and said spring means being so constructed and arranged that said spring means yieldably holds said arm in each of said positions and

neither said spring means or said arm extends rearwardly of the rear surface of said bracket at any time.
